UNITED STATES PATENT OFFICE.

RAY J. BERTHOUD, OF SWANTON, OHIO.

ANTI-RAIL-CREEPER.

1,162,968.

Specification of Letters Patent.

Patented Dec. 7, 1915.

Application filed October 13, 1915. Serial No. 55,595.

To all whom it may concern:

Be it known that I, RAY J. BERTHOUD, a citizen of the United States, residing at Swanton, in the county of Fulton and State of Ohio, have invented certain new and useful Improvements in Anti-Rail-Creepers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 A familiar difficulty encountered in railway operation,—especially in double track roads in which the traffic upon the respective tracks is in but one direction,—is the tendency of the rails to overcome their fastenings to the ties and to "creep" longitudinally. Various devices have been proposed for overcoming this difficulty, and some of the "anti-creepers" have, in a measure, proved successful. Usually in these devices 20 a slight longitudinal movement of the rail causes the anti-rail creeper to closely grip the foot of the rail and to prevent its further movement, but the rail must first move in order to cause an effective grip upon its 25 flange. Now, when the reaction from the blows of the passing car-wheels takes place, or when an opposite stress occurs from trains moving in the other direction, the hold of the gripping device is loosened and 30 before it can again properly grip the rail the rail must move slightly beyond the gripping point at which it was held in the first instance. Thus the gripping device is constantly loosening its hold and as often taking a new hold at a point slightly in advance 35 of its last preceding hold, so that while the creep of the rail is retarded it is not wholly prevented. To overcome the difficulty above indicated, some devices of this class are provided with means for positively anchoring the rail-gripping member to an adjacent cross-tie, thus adding to the number of parts, weight and expense of the device.

40 My invention is designed to provide means for overcoming the difficulties above indicated, and, more particularly, to provide a device of the character indicated which shall, independently of the movement of the rail or of any anchorage to the cross-tie, so 45 firmly grip the base or flange of the rail that the longitudinal movement of the rail will

be prevented except by a corresponding movement of the cross-tie with which the clamping device is in contact.

A further object of my invention is to 60 provide an anti-creeping device for rails which shall be light, simple, inexpensive and strong and which may be readily applied and removed.

To these ends my invention consists of the 65 construction and arrangement of parts hereinafter described, and shown and illustrated in the accompanying drawings, in which—

Figure 1 is a top-plan view of my device 70 fixed upon a track-rail and in operative relation to a cross-tie; Fig. 2, a perspective view of the approximately triangular creeping member hereinafter referred to, detached; Fig. 3, a perspective view of the wedge hereinafter referred to, detached, and Fig. 4, a 75 transverse sectional elevation of my device taken on line $x-x$, Fig. 1.

Like numerals of reference indicate like parts throughout the drawings.

In the drawings, 1 is a cross-tie and 2 a 80 track-rail of the usual construction and having an ordinary base or flange 3.

4 is a stout casting, approximately triangular in outline, each angle being provided with an upturned hook. The casting is disposed transversely of and resting against the under side of the base of the rail. Hook 5, at the more acute angle of the casting, engages one margin of the foot of the rail. Hook 6 engages the opposite margin of the 90 rail. This angle of the casting is also provided with a downwardly projecting head 7 adapted to abut against the neighboring cross-tie. The remaining angle of the casting is provided with a hook 8. The hooks 95 6 and 8 are connected by an integral bar or member 9, channeled on its inner side, as at 10. Hooks 5 and 6 being engaged with opposite margins of the base of the rail with the head 7 abutting against the neighboring 100 tie, a wedge 11 is driven between the hook 8 and the margin of the rail and into the channel 10, thus powerfully swinging the hook-portion 8 away from the rail and bringing the hooks 5 and 6 into close gripping 105 engagement with opposite margins of the base of the rail. The wedge 11 is slightly channeled on its straight edge which contacts with the edge of the rail-flange and has a downwardly projecting head to facilitate 110 the driving of the wedge into position.

While I have shown, by way of illustra-

tion, the principal member of my device as formed of integral bars, it will be understood that the device may be, if desired, cast as an integral plate having a substantially 5 triangular form. The device may be provided with suitable strengthening ribs as shown or as may be desired.

It will be seen that the device here described may be readily attached and may be 10 as readily removed by merely driving the wedge into or out of operative position. It will also be understood that these anti-creepers are applied to both rails of the track at suitable distances apart and that they may, 15 if desired, be reversed or doubled in such fashion as to prevent the movement of the rail in either direction.

Having described my invention, what I claim and desire to secure by Letters Patent, is—

1. In a device of the described character, a rigid casting approximately triangular in outline, one corner of the casting having a hook adapted for engagement with one mar-

gin of a track-rail-flange, another corner of 25 the casting having a hook adapted for engagement with the opposite margin of such flange and having a head adapted for abutment against a cross-tie, the remaining corner having a hook, combined with a wedge 30 adapted to enter between the latter hook and said opposite flange-margin.

2. A device of the described character, comprising a rigid plate having three triangularly disposed hooks, two of said hooks 35 being adapted to engage opposite margins of a track-rail-flange, one of said two hooks being joined with the remaining hook by a channeled member, and a wedge adapted to be driven between said remaining hook and 40 one of said margins and into said channel.

In testimony whereof I affix my signature in presence of two witnesses.

RAY J. BERTHOUD.
